REPRODUCING APPARATUS

William H. Meincke, White Plains, N. Y.

Application May 8, 1942, Serial No. 442,218

3 Claims. (Cl. 274—1)

This invention relates to new and useful improvements in reproducing apparatus and more particularly it pertains to an apparatus for reproducing both audibly and visually, subject matter previously recorded upon a record strip by the recording apparatus disclosed in another application filed simultaneously herewith by me.

It is an object of the present invention to provide an apparatus by means of which a preformed record may be reproduced both in audible and visual form to enable a typist to construct a true and accurate typewritten copy thereof.

In my co-pending application for recording apparatus, I have described the apparatus as used for recording court proceedings and in this application, this apparatus will be described as reproducing the record made by the recording apparatus of such a procedure.

In the drawings,

Figure 1 is a perspective view illustrating an apparatus constructed in accordance with the present invention illustrating its general appearance and manner of use,

Figure 2 is a diagrammatic view illustrating the mechanical elements of the apparatus and the electrical wiring diagram thereof, and;

Figure 3 is a fragmentary plan view of a portion of a preformed record strip bearing a record to be transcribed into typewritten form.

Referring to Figure 1 of the drawings, the reference character A designates a cabinet which is preferably of the portable type as illustrated. This cabinet forms means for housing the major portion of the apparatus which, as heretofore stated is illustrated diagrammatically in Figure 2 of the drawings.

The apparatus is operated by a preformed record strip 38 which may be of any suitable material upon which a sound track may be impressed by a sound recording apparatus and which is also capable of perforation. The record strip is also possessed of such qualities as will render it capable of being fed relatively to certain elements of the apparatus by means of a suitable mechanism similar to the film strip feeding mechanism of a motion picture camera or projector for which purpose it is provided with marginal openings for engagement by the feeding mechanism.

A section of such a record strip is illustrated in Figure 3 of the drawings. The record strip comprises a body portion 10 of relatively thin narrow form having marginal perforations 40 for engagement by feeding mechanism. A sound track 39 is impressed thereon which preferably

extends along one edge of the record strip, and it also has a plurality of longitudinally extending spaced series of perforations designated, 140, 141, 142, 143, 144 and 145. This strip is also illustrated in transverse section on an enlarged scale in Figure 2 of the drawings.

Referring to Figure 2 of the drawings, the reference character B designates an amplifier and electric current is supplied thereto by a circuit, the positive leg of which includes two conductors 20 and 21. The conductor 20 leads to the terminal 22 of a record strip rewind motor 23 which operates the record strip feeding mechanism, which however, is not herein illustrated. The conductor 21 is connected to the conductor 20 as at 24. The negative leg of this circuit consists of a conductor 25, which is connected as at 26 to the switch lever 27 of a switch 28 and a conductor 29 which leads from the contact 30 of the switch 28.

Leading from the other terminal 31 of the rewind motor 23 there is a conductor 32 which leads to the contact 33 of a switch 34, the switch lever 35 of which is connected as at 36 to a conductor 38' which in turn is connected as at 39 to the conductor 25.

The switches 28 and 34 are illustrated in Figure 1 of the drawings as foot operated types which close their respective circuits when pressure is applied and which open said circuits when the pressure is relieved. The conductors of these circuits and switches are illustrated in Figure 1 of the drawings as cords or cables which may be plugged into the cabinet A.

Leading from the terminal 39 of the driving motor 40 there is a conductor 41 which is connected to the conductor 29 as at 42 and this conductor includes a rheostat switch 43. Leading from the terminal 44 of the motor 40 which, drives the record strip feeding mechanism in the forward direction, there is a conductor 45 which is connected to the conductor 20 as at 47 and this conductor 45 includes an electro-magnet 46, the purpose of which will be hereinafter described.

From the foregoing it will be apparent that upon operation of the switch 28 by the operator, the circuit of the motor 40 will be closed and the electro-magnet 46 will be energized and upon operation of the switch 34 by the operator, the circuit to the rewind motor 23 will be closed to set this motor into operation.

Mounted in the cabinet A and movable towards and away from the record strip 38, there are a plurality of brushes 50, 51, 52, 53, 54 and 55.

These brushes are mounted in a carrier 56 which is held normally away from the record strip 38 by springs 57, its movement in this direction being limited by suitable stops 58. The carrier 56 is moved in the direction of the record strip to move the brushes into contact therewith by the electro-magnet 46, the carrier being provided with an armature 59 which is attracted to the electro-magnet 46 when the latter is energized by closing of the circuit to the motor 40 upon operation of the switch 28 as heretofore described.

Also mounted upon the carrier 56 there is a sound reproducing unit 60 and the stylus 61 of which is moved into engagement with the record strip 38 simultaneously with the several brushes 50, 51, 52, 53, 54 and 55.

The brushes 50, 51, 52, 53, 54 and 55 are so spaced upon the carrier that they track respectively with the series of perforations 140, 141, 142, 143, 144 and 145 and the sound unit 60 is so positioned thereon that its stylus 61 registers with the sound track 39 of the record strip 38.

The reference numeral 65 designates a plate mounted to the rear of the record strip 38 and this plate is electrically connected with the conductor 28 as at 66 by a conductor 67 which is connected to the conductor 28 as at 66.

The sound reproducing element 60 is connected to the amplifier A by two conductors 68 and 69 and the reference character D designates a head phone or set connected to the amplifier B by conductors 71 and 72 illustrated in Figure 1 as a cord or cable which plugs into the cabinet A.

The cabinet A has a plurality of visual signals, there being seven illustrated in the present embodiment of the invention.

The visual signal designated 75 in Figure 1 of the drawings is an indicator which shows the extent to which the record strip has passed through the feeding mechanism and consequently, the portion thereof which has been reproduced as well as the portion which has not passed in the presence of the reproducing unit. This indicator is preferably of the mechanical type and may be operated from the record strip feeding mechanism.

The remaining visual signals are preferably in the form of electric lamps which are illuminated automatically at intervals by the record strip 38 in its passage in the presence of the brushes 50, 51, 52, 53, 54 and 55 and the plate 65 and the manner in which this is accomplished will now be described.

In both Figures 1 and 2 of the drawings, these visual signals are designated by the reference numerals 50', 51', 52', 53', 54' and 55'.

Leading from the brush 50 there is a conductor 70 which leads through the lamp of the visual signal 50' and which is connected as at 78 to the conductor 20. Leading from the brush 51, there is a conductor 79 which leads through the lamp of the visual signal 51' and which is connected as at 80 to the conductor 77. Leading from the brush 52, there is a conductor 81 which leads through the lamp of the visual signal 52' and which is connected to the conductor 77 as at 82. Leading from the brush 53 there is a conductor 83 which leads through the lamp of the visual signal 53' and which is connected as at 84 to the conductor 77. Leading from the brush 54 there is a conductor 85 which leads through the lamp of the visual signal 54' and which is connected to the conductor 77 as at 86. Leading from the brush 55 there is a conductor 87 which

leads through the lamp of the visual signal 55' and which is connected as at 88 to the conductor 20.

It will be noted that the visual signal 55' is considerably larger than the remaining illuminated signals and it is desirable also to have it clearly distinguished from the others preferably by being of a different color, the purpose of which will be hereinafter described.

10 By reference to Figure 2 of the drawings it will be noted that the circuits of the several illuminated visual signals are normally open by reason of the fact that their respective brushes are out of contact with the plate 65. It will

15 also be noted that this same condition exists when the brushes are moved into position to engage the plate 65 except where any one of the brushes tracks a perforated area of the record strip 38.

20 When, however, a series of perforations presents itself to any of the several brushes, that particular brush is permitted to contact the plate 65 through the perforations and thereby complete the circuit to its corresponding visual signal 25 to illuminate the lamp thereof.

Each of the visual signals 50', 51', 52', 53', and 54' has associated therewith an identification preferably in the form of a guide into which may be inserted a suitable card which will serve 30 to indicate to the operator the identification of the sound record received through the head phones D.

Having described the apparatus, I will now give 35 a typical operation thereof in the reproduction of a record of court proceedings recorded upon the record strip 38.

As heretofore stated, the record strip 38 is preformed in a suitable recording apparatus such 40 for example as the apparatus illustrated in the application filed simultaneously herewith.

The sound track 39 upon the record strip while more or less continuous, is recorded in separate sections by a number of different persons or characters and each of the separate series of 45 perforations bears a definite relation to a section of sound tract.

For example, in a court proceeding there is an operator for the recording apparatus who replaces the court stenographer; a judge; a witness; 50 a counsel for the plaintiff, a counsel for the defendant and perhaps other persons whose various conversations would combined, form the complete recording of the sound track 39 of the record strip.

55 The manner of making the record strip 38 by the recording apparatus of my co-pending application heretofore referred to is more or less arbitrary in that any one of the series of identifying perforations may relate to the sound 60 recorded by any particular party so long as this relation is maintained throughout the recording operation, any one party, as for example, the witness, need have no identification means for his recording since the reproducer, under 65 such circumstances, would know that reproduced sound unaccompanied by any visual signal would in every instance be the recorded voice of the witness.

With the parts in their neutral or off position, 70 in which they are shown in Figure 2 and with the record strip in feeding position, the reproducing apparatus is ready for operation.

The operator exerts a pressure on the foot switch 28 to close the same, such action closes 75 the circuits heretofore described in the driving

motor 40 and the electro-magnet 46 to energize the same.

This action sets in operation, the driving motor 40 to feed the record strip forwardly and moves the carrier towards the record strip 38 sufficiently to effect engagement of the stylus 61 of the sound reproducing unit 60 and the several brushes 50, 51, 52, 53, 54 and 55 into engagement with their respective areas of the sound record strip 38.

As the record strip is fed through the apparatus, the recording of the sound track 39 is transmitted through the sound reproducing unit 60, the amplifier B and the head phones D to the operator who makes a typewritten or other copy of the subject matter thus transmitted to her.

In the foregoing manner, the apparatus continues to operate so long as the switch 28 is retained closed.

If the sound record being reproduced be the voice of the witness, there would be no visual signal to the operator.

If, however, the sound record change from the witness to another party, as for example, where the judge would intercede with a question to the witness, this portion of the sound record would have associated therewith a series of perforations, for example, the series designated 141 on the record strip 38, which series of perforations would, as this portion of the sound record was reached, permit the brush 51 contacting the plate 65 and complete the circuit to the visual signal 51' indicating that the sound record being reproduced was the voice of the judge.

It is believed that further description of this portion of the apparatus is unnecessary since it will be obvious from the foregoing that as the several brushes are permitted to contact the plate 65 the circuit to the corresponding visual signal will be established and thus the several sections of the sound record be identified through the medium of the cards carried in the guides 80.

The rheostat switch 43 permits of the adjusting the speed of operation of the driving motor 40 to her convenience.

It will be noted that the visual signal 55' is considerably larger and of a different character than are the remaining visual signals. This is for the purpose of greater certainty of attracting the operator's attention which would, under ordinary operating conditions be concentrated upon the smaller visual signals.

The visual signal 55' has a special purpose in that it signifies that that portion of sound record, whatever it may be, is to be marginally indented in the typewritten copy.

Should the operator desire to read back a portion of the record strip, she removes her foot from the switch 28, permitting it to open and thus rendering inoperative, the entire apparatus.

If, with the parts in the inoperative position, the operator closes the switch 34, the circuit heretofore described will be closed to the rewind motor to operate the film feeding mechanism in the reverse direction and rewind the desired amount of the record strip.

From the foregoing, it will be apparent that the present invention provides an apparatus by means of which a sound record which has been recorded by several persons may be reproduced and that each individual's portion of the sound record will be identified with the individual by whom it was recorded.

In view of the foregoing, it will also be obvious that the operations are carried out in such a manner as to permit of making accurate typed or otherwise scribed copies of the subject matter recorded upon a sound record strip.

Having thus described the invention, what I claim as new is:

1. Apparatus for reproducing recorded material from a preformed record which includes a plurality of separately recorded sound recordings and a plurality of separately recorded mechanical recordings in the form of separate series of perforations each of which series constitutes an identification recording for one of the separately recorded sound recordings, said apparatus comprising in combination, a plurality of visual signals, a single contact member, a group of contact members arranged in spaced relation to the single contact member and being movable into and out of position to engage the single contact member, means for feeding the preformed record between the single contact member and the individual contact members of said group to prevent contact thereof with the single contact member except through the perforations of the preformed record, means for operating one of said visual signals by each contact member of the group of contact members upon its engagement with the single contact member through one of the series of perforations in the preformed record, means for moving said group of contact members into position to engage the single contact member and the preformed record, and sound reproducing means for reproducing the separately recorded sound recordings of the preformed record.

2. Apparatus for reproducing recorded material from a preformed record including a plurality of separately recorded sound recordings and a plurality of separately recorded mechanical recordings in the form of separate series of perforations each of which series of perforations constitutes an identification recording for one of the separately recorded sound recordings, said apparatus comprising in combination, a plurality of visual signals, a single contact member, a group of contact members including a contact member for each of said visual signals, said group of contact members being movable into and out of position to engage the single contact member, means for normally holding said group of contact members out of position to engage the single contact member, means for feeding the preformed record between the single contact member and the group to prevent contact of the several contact members of the group when they are in position to engage the single contact member, except through the series of perforations of the preformed record sound mechanism including a sound reproducing unit for reproducing the separately recorded sound recordings of the preformed record, means for operating one of said visual signals by each contact member of the group of contact members, a sound mechanism for reproducing the separately recorded sound recordings, and means for moving the contact members of the group of contact members into position to engage the preformed record and the single contact member.

3. An apparatus for reproducing recorded material from a preformed record which includes a plurality of separated sound recordings and a mechanical identification recording for each of said sound recordings, said apparatus comprising in combination, a plurality of visual signals,

a single contact member, a group of contact members arranged in spaced relation to the single contact member and being movable into and out of positions to engage the single contact member, means including an electric motor for feeding the preformed record between the single contact member and the individual contact members of said group to prevent contact thereof with the single contact member except through the medium of the mechanical recordings of the preformed record, means for operating one of said visual signals by each contact member of the group of contact members upon engagement with the single contact member through the

5 medium of the mechanical recordings of the preformed record, a sound reproducing unit for reproducing the sound recording of the preformed record, a circuit for said motor, a switch for controlling said motor circuit, means included in said motor circuit for moving said group of contact members and the sound reproducing unit simultaneously into operative relation with the preformed record when the motor circuit is 10 closed, and separate means for disengaging the group of contacts and the reproducing element with the preformed record upon opening of the motor circuit.

WILLIAM H. MEINCKE.
